UNITED STATES PATENT OFFICE.

RICHARD F. OUTCAULT, OF NEW YORK, N. Y., ASSIGNOR TO THEODORE METZELER AND FREDERIC L. DENIVELLE, OF BROOKLYN, NEW YORK.

DESIGN FOR A STATUETTE.

SPECIFICATION forming part of Design No. 36,302, dated May 5, 1903:

Application filed March 25, 1903. Serial No. 149,587. Term of patent 3½ years.

To all whom it may concern:

Be it known that I, RICHARD F. OUTCAULT, a citizen of the United States, and a resident of the city of New York, (Flushing, borough of Queens,) in the county of Queens and State of New York, have invented a new, original, and ornamental Design for a Statuette, of which the following is a full, clear, and exact description.

10 Reference is to be had to the accompanying drawing, forming a part of this specification, in which the figure is a side elevation of a statuette, showing my design.

The design consists in a base supporting 15 the representation of a nondescript dog, appearing with a smiling face and sitting on its haunches alongside the boy, the latter appearing in an erect standing position.

The leading feature of the design consists in the representation of the mischievous boy and the nondescript dog.

Having thus described my invention, I claim as new and desire to secure by Letters Patent—

The ornamental design for a statuette as 25 herein shown and described.

In testimony whereof I have signed my name to this specification in the presence of two subscribing witnesses.

RICHARD F. OUTCAULT.
